[57] CLAIM

The ornamental design for a snap top beverage can opener, substantially as shown and described.

DESCRIPTION

FIG. 1 is a front elevational view of a snap top beverage can opener showing our new design;

FIG. 2 is a right side elevational view thereof, the opposite side being a mirror image;

FIG. 3 is a top plan view thereof;

FIG. 4 is a bottom plan view thereof; and

FIG. 5 is a rear elevational view thereof.
